John T. Ashbrooke
BY Stearlo Perry
ATTORNEY

UNITED STATES PATENT OFFICE.

JOHN T. ASHBROOKE, OF NEW YORK, N. Y., ASSIGNOR TO THE BONNIE-B COMPANY, INC., A CORPORATION OF NEW YORK.

DESIGN FOR A DISPLAY CABINET.

Application filed July 20, 1921. Serial No. 486,274. Term of patent 3½ years.

To all whom it may concern:

Be it known that I, JOHN T. ASHBROOKE, a citizen of the United States of America, and resident of New York city, in the county of New York and State of New York, have invented a new, original, and ornamental Design for Display Cabinet, of which the following is a specification, reference being had to the accompanying drawing, forming part thereof.

I claim:

The ornamental design for a display cabinet, as shown.

JOHN T. ASHBROOKE.

Witnesses:

BERTRAND D. DEPIERRIS,
SADIE H. OLICKER.
